DESIGN FOR A FLASHLIGHT SWITCH

Emerson H. Tompkins, Waterbury, Conn., assignor to Scovill Manufacturing Company, Waterbury, Conn., a corporation of Connecticut

Application November 21, 1936, Serial No. 66,052

Term of patent 14 years

To all whom it may concern:

Be it known that I, Emerson H. Tompkins, a citizen of the United States of America, residing at Waterbury, in the county of New Haven and State of Connecticut, have invented a new, original, and ornamental Design for a Flashlight Switch, of which the following is a specification, reference being had to the accompanying drawing, forming a part thereof.

Fig. 1 is a plan view of the flashlight switch, embodying my new design.

Fig. 2 is a side view of the same.

Fig. 3 is an end view of the same.

I claim:

The ornamental design for a flashlight switch substantially as shown.

EMERSON H. TOMPKINS.
